(57) **CLAIM**

The ornamental design for a beverage container as shown and described.

DESCRIPTION

FIG. 1 is a top perspective view from above of my new design for a beverage container, shown in a closed configuration;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof, shown in an open configuration;

FIG. 8 is a top plan view thereof, shown in a closed configuration;

FIG. 9 is a cross-sectional view taken along line 9-9 in FIG. 7; and,

FIG. 10 is a bottom plan view thereof.

The ornamental design which is claimed is shown in solid lines in the drawings. The portions of the beverage container shown in broken lines form no part of the claimed design. The broken line cross-sectional hatching in FIG. 9 depicts portions of the beverage container that form no part of the claimed design.
